UNITED STATES PATENT OFFICE.

JOHN MATTHEWS, OF NEW YORK, N. Y.

DESIGN FOR A DISPENSING-COLUMN.

SPECIFICATION forming part of Design No. 13,011, dated June 27, 1882.

Application filed December 12, 1881. Term of patent 14 years.

To all whom it may concern:

Be it known that I, JOHN MATTHEWS, a citizen of the United States, residing at New York, in the county and State of New York, have invented and produced a new and original Design of a Dispensing-Column, of which the following is a specification, reference being had to the accompanying engraving, forming part thereof.

My design consists of a circular base, C, provided with radiating stalls. From the center of this base rises a tapering column, A, having an enlargement, from which the draft-arms B B B B project for dispensing beverages. Above each draft-arm is an ornamental label engraved with the name of the beverage. The top of the column is flaring, and forms a

receiver, D, which is surmounted with a glass shade, E, of a bulbous or globular form. On the receiver, and under the glass shade, may be placed drinking-tumblers or a block of ice, or a fountain jet of water may be arranged to play inside the glass shade. Inside the glass shade is an ornamental wire screen, F.

I claim—

The design for a dispensing-column herein shown and described, consisting of the base C, receiver D, and bulb-shaped glass shade E, all arranged substantially as described.

JOHN MATTHEWS.
